C. E. STACY

DUPLEX APERTURE MOUTHPIECE

Filed Nov. 21, 1921

Inventor:

Charles E. Stacy.

R. S. Berry,
Attorney.

UNITED STATES PATENT OFFICE.

CHARLES E. STACY, OF LOS ANGELES, CALIFORNIA, ASSIGNOR TO FRANK C. OLDS,
OF LOS ANGELES, CALIFORNIA.

DUPLEX-APERTURE MOUTHPIECE.

Application filed November 21, 1921. Serial No. 516,793.

To all whom it may concern:

Be it known that I, CHARLES E. STACY, a citizen of the United States, residing at Los Angeles, in the county of Los Angeles 5 and State of California, have invented new and useful Improvements in Duplex-Aperture Mouthpieces, of which the following is a specification.

My invention relates to band wind instruments where sound is produced by the use of air blown through a mouthpiece such as, cornets, trombones, baritones, altos, horns and tubas or like instruments and more particularly to the mouth piece for such instruments.

The principal object is to provide a mouth piece with a plunger having an opening of more than one aperture.

Another object is to provide a mouth piece 20 with a plunger having apertures of different sizes and shapes.

A further object is to provide a mouth piece for wind instruments that can be operated with the fingers to suit the convenience 25 of an operator of such instruments.

A still further object is to provide a mouth piece having a plunger under spring tension and normally positioned for one aperture.

I use a small throat for notes of a high 30 register and a large throat for notes of a low register so that an operator may optionally play notes of either register at will and the operator will have access to the two 35 size throats while playing thereby increasing the ease of playing in the extreme registers.

Other objects will hereinafter appear, being more fully described and stated in the 40 claims, references being had to the accompanying drawing, in which:

Fig. 1 is a perspective view of the assembled mouthpiece.

Fig. 2 is a vertical section on the line 2—2 45 of Fig. 1 to more clearly show the operating parts.

Fig. 3 is a vertical cross section on the line 3—3 of Fig. 2 as seen looking in the direction dictated by the arrows.

Figure 4, is a detail in horizontal section 50 as seen on the line 4—4 of Figure 2.

More specifically, 9 indicates a tube having a mouthpiece 10, such as is commonly used on band wind instruments.

Interposed between the tube and mouth-

piece and extending at right angles thereto is a cylindrical casing 11, which projects from opposite sides of the tube with its longitudinal center on a plane with the center of the tube.

The tube and mouthpiece open to the interior of the casing on diametrically opposite sides thereof. Slidably mounted in the casing is a plunger 12, provided with a pair of transverse apertures 13 and 14 constituting low-tone and high-tone apertures respectively, and which apertures are designed to register with the openings of the tube and mouthpiece. The low-tone aperture 13, is of straight bore and substantially of the same 70 diameter as the bore 31 in the tube 9. The high-tone aperture 14 is of a shape in longitudinal section substantially the same as that of a Venturi tube, that is, with a reduced throat of smaller diameter as indicated at 75 32, located nearer the periphery than to the center of the plunger 12, the bore of the throat flaring abruptly and smoothly to substantially the size of the orifice 33 at the inner end of the mouthpiece and flaring 80 gently in the opposite direction from the smallest diameter 32 towards the opposite side of the plunger 12, where it reaches substantially the size of the bore 31 of the tube 9. The high-tone aperture is thus 85 formed so that when it is in register with the mouthpiece and air is blown therethrough the air approaching the throat will easily flow to the small diameter and gradually expand into the tube without swirling.

The plunger 11 has a counter-bore 15 in the lower end 16 thereof in which is seated one end of an expansible coil spring 17, which encircles a pin 18 affixed to the 95 plunger and extending through an opening in a cap 19 screwed on the lower end portion of the casing. The cap 19 bears on the spring to compress the latter and place it under compression whereby the spring will 100 act to yieldably oppose movement of the plunger in one direction. Movement of the plunger under action of the spring is limited by an end wall 11^a formed on the upper end portion of the casing. The spring normally 105 maintains the plunger in an uppermost position with the high-tone aperture 14 aligned and in register with the passage through the tube and mouthpiece. Fixed in the upper end 21 of the plunger 12, is a pin which 110

projects through an opening in the end wall 11^a and is provided with a button 23, forming a seat for the finger by which the plunger may be manually depressed.

5 Formed in the upper portion of the side wall of the casing is a slot 24 through which a finger pin 25 carried by the plunger extends. The outer end portion 26 of the finger-pin is flattened to form a seat for the finger so that an operator may readily press the plunger downwardly from the side of the casing. The pin extending through the slot may serve to hold the plunger against rotation so that the apertures in the latter 10 will align with the passage through the tube and mouthpiece. The lower end portion 26 of the pin 18 is bent to extend horizontally beyond one side of the cylinder and flattened to form a surface for a finger by which the 15 plunger may be manually depressed from the lower portion of the casing. The mouth 28 of the mouthpiece is flared to provide a rounded surface 29 for an operator's lips, and a rim 30 extends around the flare of the 20 mouthpiece.

25 The upper wall 11^a of the casing, and the cap 19 are formed with openings through which the stem 22 and pin 18 extend, which openings serve to vent the casing above and 30 below the plunger.

The operation of the invention is apparent from the foregoing, it being seen that the plunger will be normally disposed in its uppermost position by action of the spring 17 35 with the high-tone aperture open to the tube and mouthpiece. When it is desired to change to the low-tone aperture the operator depresses the plunger either by pressing the button 22 or the finger pieces 25 and 26 according to convenience; the plunger being 40 depressed in opposition to the spring and held manually in the depressed position and in which position the low-tone aperture 13 will align with the passage through the tube 45 and mouthpiece. It will now be seen that the operator of the instrument may change from high-tone to low-tone or vice versa, while playing the instrument.

I claim:

1. A mouthpiece for wind instruments comprising a mouthpiece element, a tube having a passage to communicate with the mouthpiece element, a casing interposed between said tube and mouthpiece, a plunger having transverse apertures adapted to be moved in and out of register with the passage through said mouthpiece and tube, and means for normally holding said plunger with one of the apertures aligned with the tube.

60 2. A mouthpiece for wind instruments comprising a tube, a mouthpiece element, a casing interposed between said tube and mouthpiece, a plunger slidably mounted in said casing having a plurality of apertures therethrough, yieldable means for normally holding said plunger with one of the apertures registering with the tube and the mouthpiece, and a finger piece on said plunger whereby the latter may be manually depressed to dispose the other of the apertures 65 in register with the tube and mouthpiece.

70 3. A mouthpiece for wind instruments comprising a tube, provided with a bore, a mouthpiece, a plunger slidably transversally of said tube having a plurality of apertures therethrough of different diameters, a spring acting on said plunger to yieldably oppose depression of the plunger and serving to normally position the plunger with 75 one of the apertures in register with the bore of the tube.

4. A mouthpiece for wind instruments comprising a casing, a tube having a bore opening to said casing, a mouthpiece opening to said casing opposite the bore, a plunger mounted to reciprocate in said casing transversally of the tube having a plurality of apertures of different diameters adapted to be positioned in register with the bore of 80 the tube, means whereby said plunger may be depressed from the exterior of said casing, and a spring for opposing depression of the plunger and for restoring it to a normal 85 position.

CHARLES E. STACY.
